EGG EXTRACTOR

Harry Becker, St. Louis, Mo.

Application February 25, 1952, Serial No. 18,658

Term of patent 14 years

(Cl. D44—4)

To all whom it may concern:

Be it known that I, Harry Becker, a citizen of the United States, residing in the city of St. Louis and State of Missouri, have invented a new, original, and ornamental Design for an Egg Extractor, of which the following is a specification, reference being had to the accompanying drawing, forming part thereof.

Figure 1 is a perspective view of an egg extractor, showing my new design; and

Figure 2 is a bottom view of the same, on an enlarged scale.

I claim:

The ornamental design for an egg extractor, as shown.

HARRY BECKER.
